UNITED STATES PATENT OFFICE.

EDWARD I. MARSHALL, OF FOSTER, NEBRASKA.

FOOT ACCELERATOR.

Application filed January 13, 1926. Serial No. 80,989.

The present invention relates to improvements in foot accelerators for use particularly on motor vehicles of the Ford type.

One of the important objects of the present invention is to provide a highly novel and simple means whereby the throttle may be actuated either by foot or by hand independently of each other.

A further object is to provide a foot accelerator of the above mentioned character whereby the means provided for returning the foot actuating mechanism to its normal position will not interfere with the usual hand throttle lever mounted on the steering column of a Ford automobile when said lever has been moved to a predetermined position.

A further object is to provide a foot accelerator of the above mentioned character which may be readily and easily installed without necessitating any material alterations of the parts of the vehicle with which the same is adapted to be associated.

A still further object is to provide a foot accelerator of the above mentioned character which is simple in construction, inexpensive, strong and durable and further well adapted to the purpose for which it is designated.

Other objects and advantages of the invention will become apparent from the following description taken in connection with the accompanying drawing.

In the accompanying drawing forming a part of this application, and in which like numerals designate like parts throughout the same:

Figure 1 is a side elevation of the foot accelerator embodying my invention.

Figure 2 is a top plan view thereof, and

Figure 3 is a detail perspective view of the rectangular plate.

In the drawing, wherein for the purpose of illustration is shown the preferred embodiment of my invention, the numeral 1 designates generally the throttle lever of a carburetor such as is mounted on an internal combustion engine of an automobile of the Ford type.

The carburetor in the present instance is indicated at 2, the usual arm 3 extends laterally from the upper end of the throttle lever 1, and is provided at its outer end with an eye portion 4.

A substantially triangular shaped plate 5 is disposed beneath the arm 3, and the apex thereof is provided with a suitable opening

which is adapted to register with the apertured head 4 for receiving the bolt 6. A substantially rectangular shaped plate 7 is provided with an opening 8 in the rear end portion thereof and through which the bolt 6 is also adapted to extend, this plate 7 being disposed above the outer end of the arm 3 in the manner as more clearly illustrated in Figure 1.

A pair of depending fingers 9 are formed on the forward end of the rectangular plate 7, the same extending downwardly on opposite sides of the arm 3 and passing through suitable openings 10 provided therefor in the triangular shaped plate 5. The lower free end of these fingers are curved upwardly to provide hooks 11 whereby the fingers are prevented from becoming accidentally disengaged from the openings 10 that are provided therefor in the triangular shaped plate 5. An upstanding flange 12 is formed at one of the longitudinal side edges of the rectangular shaped plate 7 and a longitudinal slot 13 is formed in the aforementioned flange. The construction of the plate is more clearly disclosed in Figure 3 of the drawing.

The usual rod which connects the throttle of the carburetor with the throttle lever mounted on the steering column, not shown, is indicated at 14. The forward end of this rod is disposed laterally and the free end of the laterally disposed portion 15 of this rod extends through the slot 13 provided in the flange 12 and is disposed downwardly as indicated at 16 so as to prevent the accidental displacement of the rod from the rectangular shaped plate, thus providing a connection between the rod 14 and the throttle lever 1. The opposite end of the rod 14 is adapted to be connected to the usual hand lever mounted on the steering column in the usual manner.

The foot accelerator further includes an elongated rod, the intermediate portion 17 of which is journaled in suitable brackets 18 secured to the under side of the top floor board 19. One end of the rod is disposed upwardly through the floor board in a suitable slot provided therefor, or opening such as is indicated at 20, said end portion of the rod being then disposed forwardly as indicated at 21, and supporting on its free end the foot engaging plate 22. The other end 110 of the rod is disposed downwardly as indicated at 23, and the lower free end is flat-

tened as illustrated at 24, and the flattened portion 24 is provided with a suitable opening 25 through which extends the rear end of an elongated rod 26. A head 27 is provided on the extreme rear end of this rod to prevent its displacement from the lower end 24 of the rod providing the foot lever. The forward end of this rod 26 is disposed laterally as at 28 and thence forwardly as at 29.

10 The free end of the forwardly disposed portion 29 of said rod 26 terminates in an angular foot or hook 30 which extends through a suitable opening provided in the innermost end of the triangular shaped plate 5.

15 A relatively light coil spring 31 is secured at one end to the other corner of the triangular plate 5 and at its opposite end to the carburetor 2 such as by attaching the 20 spring around the needle valve 32. This coil spring provides a means for returning the triangular shaped plate 5 and the throttle lever 1 to its normal position when the hand lever associated with the rod 14 is in 25 its retarded position.

30 A relatively heavy coil spring 33 is secured at its upper end to the under side of the top floor board 19 at a point forwardly of the intermediate portion 17 of the rod forming a part of the foot lever, the lower end of the coil spring 33 being secured to the downwardly projecting portion 23 at a point adjacent the flattened lower end 24.

35 It is obvious that when the usual hand lever as associated with the upper end of the rod 14 is actuated, the triangular shaped plate 5 will be moved laterally with respect to the throttle lever 1, and due to the downwardly disposed fingers 9 and 11 which engage the respective sides of the arm 3, the 40 arm will be operated to effect the actuation of the throttle lever 1, and the throttle plate associated therewithin the carburetor. This 45 operation will in no way interfere or effect the actuation of the foot accelerator and the hand throttle lever may be set at any desired position.

50 In order to permit the throttle lever to be actuated by the operator of the vehicle without necessitating the use of the hands, the foot engages the plate 22 of the foot lever 21 causing the intermediate portion 17 of the rod to rotate in its bearing and simultaneously cause the downwardly projecting portion 23 to move rearwardly and thereupon cause the flattened end 24 to engage the head 27 of the rod 26 whereby a rearward pull on the rod 26 is exerted. As the rod 26 moves rearwardly, the hooked end 30 of said 60 rod will also swing the triangular shaped plate 5 and due to the connection between the arm 3 and the plate 5 by reason of the depending fingers 9 and 11, said arm will operate simultaneously with the plate, and thereby cause the throttle lever 1 to be ac-

65 tuated for effecting the opening of the throttle plate within the carburetor. It is of course understood that during the swinging movement of the plates 5 and 7, simultaneously with the arm 3 of the throttle lever 1, when the foot accelerator is actuated that the hooked end 16 of the rod 14 will slide in the longitudinal slot 13 formed in the up- 70 standing flange 12.

75 As soon as the foot is released from the plate 22, the coil spring 33 will automatically return the parts to their normal positions, and thus close the throttle plates. It is also to be understood that when the hand lever is actuated for effecting the operation 80 of the throttle lever, that the rod 26 which is associated with the foot lever will slide rearwardly through the aperture 25 provided therefor in the flattened end portion 24 of the foot lever rod, so that the hand 85 lever and the foot lever will operate independently of each other.

90 The simplicity in which my device is constructed enables the same to be readily and easily attached on the carburetor of an internal combustion engine of the type such as are used on Ford automobiles without necessitating any material alteration of the parts of the vehicle with which my device is to be associated. Furthermore, by constructing a 95 foot accelerator of the above mentioned character, the hand lever which is associated with the throttle lever may be actuated and set in any desired position without any possibility of the spring associated with the foot lever returning the parts to their normal 100 positions.

105 While I have shown the preferred embodiment of my invention it is to be understood that minor changes in the size, shape and arrangement of parts may be resorted to without departing from the spirit and scope of the appended claims.

110 Having thus described the invention, what I claim as new and desire to secure by Letters Patent is:

115 1. In combination with the throttle lever of a carburetor including the usual laterally extending arm associated therewith, of a plate disposed below the arm, an additional plate disposed above said arm, a bolt extending through the outer end of the arm and through the adjacent ends of the plate, a pair of depending fingers formed on the upper plate and extending downwardly adjacent the opposed sides of the laterally extending arm of the throttle lever, the lower ends of said fingers extending through the adjacent end of the lower plate, the lower 120 free ends of the fingers being disposed upwardly to provide hooks for engagement with the lower plate to prevent the accidental displacement of the fingers from said lower plate, said fingers providing a means whereby the plate and the arm of the throt- 125 130

tle lever are adapted for simultaneous operation, a foot control rod secured to the lower plate, and a hand control rod secured to the upper plate.

- 5 2. In combination with the throttle lever
of a carburetor including the usual laterally
extending arm associated therewith, of a
plate disposed below the arm, an additional
plate disposed above said arm, a bolt extend-
10 ing through the outer end of the arm and
through the adjacent ends of the plate, a
pair of depending fingers formed on the up-
per plate and extending downwardly adjac-
15 ent the opposite sides of the laterally ex-
tending arm of the throttle lever, the lower
ends of said fingers extending through the
adjacent end of the lower plate, the lower
free ends of the fingers being disposed up-
20 wardly to provide hooks for engagement
with the lower plate to prevent the acci-
dental displacement of the fingers from said
lower plate, said fingers providing a means
whereby the plate and the arm of the throt-
25 tle lever are adapted for simultaneous op-
eration, an upstanding flange formed on the
upper plate, and provided with the longi-
tudinally extending slot, a hand operated
rod having its forward end extending
30 through said slot and disposed downwardly
for engagement with the side of the flange,
and a foot actuated rod secured to the lower
plate.

3. In combination with the throttle lever
of a carburetor including the usual laterally
extending arm associated therewith, of a
plate disposed below the arm, an additional
plate disposed above said arm, a bolt extend-
35 ing through the outer end of the arm and
through the adjacent ends of the plate, a
pair of depending fingers formed on the up-
per plate and extending downwardly adjac-
40 ent the opposite sides of the laterally ex-
tending arm of the throttle lever, the lower
ends of said fingers extending through the
adjacent end of the lower plate, the lower
free ends of the fingers being disposed up-
45 wardly to provide hooks for engagement
with the lower plate to prevent the acci-
dental displacement of the fingers from said
lower plate, said fingers providing a means

50

tudinally extending slot, a hand operated rod having its forward end extending through said slot and disposed downwardly for engagement with the side of the flange, a foot actuated rod secured to the lower plate, and a foot lever for actuating the last mentioned rod, the rear end of the rod being adapted for slidable movement through the foot lever when the hand operated rod is actuated, and vice versa. 55

4. In combination with the throttle lever
of a carburetor including the usual laterally
extending arm associated therewith, of a
plate disposed below the arm, an additional
plate disposed above said arm, a bolt extend-
50 ing through the outer end of the arm and
through the adjacent ends of the plate, a
pair of depending fingers formed on the up-
per plate and extending downwardly adjac-
55 ent the opposite sides of the laterally ex-
tending arm of the throttle lever, the lower
ends of said fingers extending through the
adjacent end of the lower plate, the lower
free ends of the fingers being disposed up-
60 wardly to provide hooks for engagement
with the lower plate to prevent the acci-
dental displacement of the fingers from said
lower plate, said fingers providing a means
whereby the plate and the arm of the throt-
65 tle lever are adapted for simultaneous op-
eration, an upstanding flange formed on the
upper plate, and provided with the longi-
tudinally extending slot, a hand operated
rod having its forward end extending
70 through said slot and disposed downwardly
for engagement with the side of the flange,
a foot actuated rod secured to the lower
plate, and a foot pedal for actuating the last
mentioned rod, the rear end of the rod being
75 adapted for slidable movement through
the foot lever when the hand operated rod
is actuated, and vice versa, and means for
returning the movable parts to their normal
80 positions. 85

In testimony whereof I affix my signature.
EDWARD I. MARSHALL. 90

whereby the plate and the arm of the throttle lever are adapted for simultaneous operation, an upstanding flange formed on the upper plate, and provided with the longitudinally extending slot, a hand operated rod having its forward end extending through said slot and disposed downwardly for engagement with the side of the flange, a foot actuated rod secured to the lower plate, and a foot lever for actuating the last mentioned rod, the rear end of the rod being adapted for slidable movement through the foot lever when the hand operated rod is actuated, and vice versa. 55 60

4. In combination with the throttle lever 65
of a carburetor including the usual laterally
extending arm associated therewith, of
a plate disposed below the arm, an additional
plate disposed above said arm, a bolt
extending through the outer end of the arm
and through the adjacent ends of the plate,
a pair of depending fingers formed on the
upper plate and extending downwardly ad- 70
jacent the opposite sides of the laterally ex-
tending arm of the throttle lever, the lower
ends of said fingers extending through the
adjacent end of the lower plate, the lower
free ends of the fingers being disposed up- 80
wardly to provide hooks for engagement
with the lower plate to prevent the acciden-
tal displacement of the fingers from said
lower plate, said fingers providing a means
whereby the plate and the arm of the throt-
tle lever are adapted for simultaneous op- 85
eration, an upstanding flange formed on the
upper plate, and provided with the longitudinally extending slot, a hand operated
rod having its forward end extending
through said slot and disposed downwardly
for engagement with the side of the flange, 90
a foot actuated rod secured to the lower
plate, and a foot pedal for actuating the last
mentioned rod, the rear end of the rod being
adapted for slidable movement through
the foot lever when the hand operated rod
is actuated, and vice versa, and means for
returning the movable parts to their normal
positions. 95

In testimony whereof I affix my signature.
EDWARD I. MARSHALL.
